UNITED STATES PATENT OFFICE

ONESIPPE PACALIN, OF NEW YORK, N. Y.

IMPROVEMENT IN BOOTS AND SHOES.

Specification forming part of Letters Patent No. **55,698**, dated June 19, 1866.

To all whom it may concern:

Be it known that I, O. PACALIN, of the city, county, and State of New York, have made a certain new and useful Improvement in Boots, Shoes, &c.; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which the same letters in the different figures refer to corresponding parts.

Figure 1 is a central vertical longitudinal section. Fig. 2 is an upper view of the inner plate. Fig. 3 is a side view of the plates with the leathern portions of the sole and the upper removed.

The improvement consists of an inner and outer plate, preferably of metal, between which the sole is fastened by bolts or rivets, a heel projecting down from the lower plate, and containing a heel-plug, which is fastened by a bolt, which penetrates both the upper and lower plates, being reached through an opening in the lower surface of the heel-plug or the upper surface of the inside plate.

In the drawings, A A is the inner plate, or "upper plate," as it may be appropriately called, and B B is the lower or outer plate. These embrace between them the sole C and the lower portion of the split insole, and are attached by the rivets or bolts D D D.

The upper-leather of the shoe is fitted and brought down in the usual way and whipped together, being embraced between the plates A B, the upper one being covered with the upper portion of the split insole.

From the lower plate, B, projects a heel-socket, E, which is strengthened by an angle-piece, F, at its forward edge. The socket contains a plug, G, of any suitable material, which is secured by a bolt, H, whose head is on the upper side of plate A and whose neck is in the recess I of the heel-plug; or the heel-screw may have two nuts, one inside the heel, to fasten together the two metal plates, and the other outside the heel, to fasten to the same base such substance as may be inserted into the cavity of the heel.

Having described my invention, what I claim as new, and desire to secure by Letters Patent, is—

The combination of the inner and outer plates, A B, heel-socket E, plug G, bolt H, and fastenings D D, &c., constructed and arranged substantially as described and represented.

The above specification of my improvement in boots, shoes, clogs, &c., signed this 26th day of April, 1866.

O. PACALIN.
